MANIFOLDING PACKET

John Q. Sherman, Dayton, Ohio

Application March 22, 1934, Serial No. 716,807

7 Claims. (Cl. 282—12)

This invention relates to manifolding material and more particularly to a packet of multiple superposed record strips and interleaved transfer material usable therewith for ready insertion into a strip dispensing apparatus.

The present manifolding packet is adapted for use in a portable pack holder or manifolding register of a type wherein the transfer material is stationarily held while the record material is advanced relative thereto into writing position. Such suitable pack holder or portable manifolding register is illustrated and described in Patent No. 2,072,134, March 2, 1937, resulting from co-pending application Serial No. 677,629, June 26, 1933, of which the present application is a continuation in part, and wherein the subject matter of the present application was before disclosed. Obviously the present manifolding packet and component materials may be used with other forms of dispensing apparatus. Reference is herein made to said companion application merely for illustrative purposes and with no intent nor purpose of unduly limiting the scope or application of the invention.

The object of the invention is to provide a manifolding packet which will be simple and economical in manufacture, and capable of being easily and readily assembled at the time of manufacture ready for instant use by the purchaser.

A further and important object of the invention is to provide a relatively small quantity of transfer material progressively usable with a relatively large amount of record material, and to assemble such transfer material in relation with the record material in compact form for convenient use.

A further object of the invention is to provide an improved transfer sheet having means for engaging the sheet with suitable retaining means within a supply container of a strip dispensing apparatus.

A further object of the invention is to provide a transfer sheet which will not offset or mark the forms by pressure or tracking of the strips upon the dispensing apparatus during movement into writing position.

A further object of the invention is to provide a transfer sheet usable with reversely folded record strips wherein the record strips are progressively fed from a dispensing apparatus independently of the transfer material.

A further object of the invention is to provide a transfer sheet engageable interiorly of a strip dispensing apparatus from which the sheet is adapted to extend in reverse direction inter-

mediate superposed record strips into a writing position.

A further object is to have a transfer sheet with a section as an integral part thereof which provides anchorage for the transfer sheet within the container in a non-transfer area.

A further object is a completely assembled, quick loading, multiform packet and interleaved transfer medium ready for instantaneous loading into a manifolding container.

A further object of the invention is to provide a manifolding packet and component parts having the advantageous characteristics and meritorious features hereinafter mentioned.

With the above primary and other incidental objects in view, as will more fully appear in the specification, the invention consists of the features of construction, the parts and combinations thereof, or their equivalents, as hereinafter described and set forth in the claims.

In the drawing wherein is shown the preferred, but obviously not necessarily the only form of embodiment of the invention, Fig. 1 is a perspective view of a manifolding packet embodying the present invention. Fig. 2 is a perspective view of the transfer sheet removed from the packet. Figs. 3 and 4 illustrate modifications thereof. Fig. 5 is a perspective view of a modification of the transfer sheet anchoring means.

Like parts are indicated by similar characters of reference throughout the several views.

The present packet is especially applicable to pack holders or manifolding registers wherein successive portions of the record strips are intermittently advanced from a supply compartment into writing position independently of the transfer material. The transfer sheet is adapted to be stationarily anchored interiorly of the supply compartment from which the record strips are dispensed, and to extend thence exteriorly of the compartment and in reversely folded relation between the record strips into the writing position, and is of such character and quality that it is usable repeatedly with successive portions of the record strips until the strips are exhausted. Reference is made to the companion application Serial No. 677,629 for illustration of such typical strips dispensing apparatus.

Referring to the drawing, 1 is a manifolding packet wherein multiple superposed strips 2—2 of record material comprising successions of series connected detachable forms, are collectively folded at spaced intervals into zig-zag formation, preferably although not necessarily coincident with transverse weakening division lines. While

only two such strips 2 are shown, the packet may comprise a greater number of such strips of forms.

Interleaved between the terminal portions of the folded record strips is a transfer sheet 3 of carbonized material. The transfer sheet 3 is of greater length than one of the detachable sections of the record material, but preferably less than the combined length of two such sections, and will transversely fold at 4 in conformity with the folds 5 of the record strips. Thus the carbonized portion 3a of the transfer sheet is substantially coextensive with one of the detachable sections of the record strips, but preferably has cutout grasp areas 6a, or terminates slightly short of the ends of the strips as in Fig. 1 to enable the record strips 2 to be grasped independently of the record material when being removed by hand for advancement relative thereto. The continuing portion 3b of the transfer sheet 3 extends into overlapping relation with the next succeeding sections of the record strips. Such continuing portion 3b may be an integral portion of the carbonized material or it may if desired be uncarbonized or a material of different character to which the carbonized portion 3a is joined as at 7 in Fig. 3.

When loaded into a pack holder or manifolding register with the terminal portions of the record strips and interleaved transfer portion 3a reversely folded into writing position over a suitable writing tablet, the continuing portion 3b will extend in reverse direction, interiorly of the supply compartment beneath the writing tablet about which the assembly of record and interleaved transfer material is folded. At its inner end the transfer sheet 3 is provided with suitable means for engagement with sheet retaining means within the supply compartment of the strip dispensing apparatus. In Figs. 1, 2 and 3 such engagement means is illustrated as a strip 8 of cardboard or the like arranged transversely of the transfer sheet, to which the end of the sheet is permanently attached. The supporting or attachment strip 8 is of greater length than the width of the transfer sheet and its ends protrude beyond the side margins of the transfer sheet and the record strips between which the sheet is assembled, as shown in Fig. 1, for engagement with suitable stop or retaining means provided with the supply compartment of a strip dispensing apparatus. In Fig. 4 there is shown an alternative engagement means wherein the end of the transfer sheet is reinforced by a strip 9 pasted thereto and having therein holes 10 for engagement of suitable retaining means within a dispensing apparatus.

Ordinarily a dispensing apparatus such as hereinbefore referred to is provided with strip engaging means for limiting the withdrawal of the record strips to predetermined lengths, or for aligning, registering or holding the withdrawn portions. To prevent offsetting or transfer of carbon marks to the strips as they are drawn past such engaging means and to enable the aligning, registering or holding means to engage the strips without interference with or damage from the transfer sheet, such transfer sheet may be provided with cutouts to receive the strip engaging means. These cutouts may comprise simple holes 11 in the sheet, or may be marginal indentations 12 as shown in Fig. 4. Such cutouts being positioned to agree with the strip engaging projections of the dispensing apparatus afford clearance and enable avoidance of the strip engaging

means. A transfer sheet without cutouts would not avoid being influenced by the strip engaging means but can be used and would prevent offsetting or marking of the continuous forms while being withdrawn when under pressure by the form holding means.

The assembly affords a compact inexpensive packet which enables a dispensing apparatus to be quickly loaded without necessity of adjusting the materials and interleaving the transfer material. The packet assembly is manufactured ready to be dropped into the dispensing apparatus in a position for immediate use.

In Fig. 5 there is shown a further variation wherein the ends of the anchor or supporting strip 8 are somewhat longer than in the preceding views and are bent downwardly at right angles at the sides of the packet for engagement within the end wall of a box-like container indicated by dotted lines. In such instance the reversely turned inner portion of the transfer sheets extends but a limited distance beyond the fold line of the forms.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute, the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

Having thus described my invention, I claim:

1. A manifolding packet including multiple superposed record strips collectively folded at spaced intervals into zigzag formation, and relatively short lengths of transfer material interleaved between the record strips in overlapping relation with two succeeding portions of the strips, said lengths of transfer material being reversely folded into conformity with a fold of the record strips, intermediate the overlapped portions, and transverse supporting strips to which one end of each of the transfer sheets is attached, the ends of which supporting strips project laterally beyond the side margins of the record strips for engagement with means for stationarily anchoring the transfer material while leaving the strips free for independent longitudinal movement.

2. A manifolding packet including multiple superposed record strips collectively folded at spaced intervals into zigzag formation, relatively short sheets of transfer material interleaved between the record strips, said transfer sheets being of greater length than the length of strip material between successive folds but less than two such lengths, and folded once in conformity with a fold of the record strips, and means for anchoring said transfer sheets engageable with sheet retaining means of a strip dispensing apparatus for holding the transfer strips against travel motion while the strips are being advanced relative thereto.

3. A manifolding packet including multiple superposed record strips collectively folded at spaced intervals into zigzag formation, relatively short sheets of transfer material interleaved between the record strips, said transfer sheets being disposed in overlapping relation with two succeeding lengths of strips and folded in conformity with the intermediate fold of such lengths of the strips, and retainer engaging means carried by the transfer sheets and engageable with means for holding the sheets against travel motion while the strips are being advanced relative thereto. 5
4. As an article of manufacture, a manifolding packet including multiple superposed record strips of series connected detachable forms reversely folded at spaced intervals into zigzag formation, and of which the initial set of forms provides a tablet on which indicia may be inscribed, sheets of transfer material interleaved between the terminal portions of the record strips in overlapping relation with two succeeding sets of detachable forms and collectively folded therewith, and anchor bars to which the transfer sheets are attached extending transversely between the record strips and projecting laterally beyond the lateral margins of the strips for engagement with a strip dispensing apparatus for holding said transfer sheets against travel motion during advance movement of the strips relative thereto in stationary writing position. 10
5. A cartridge type manifolding packet for quick loading of an autographic register including multiple superposed continuous record strips collectively folded at spaced intervals in zigzag formation into a succession of layers, and an interleaved relatively short length of transfer material longer than the length of the folds of the zig-zag folded strips and reversely folded about the end of a layer thereof in conformity with folds of the strips, said length of interleaved material comprising a carbonized portion interleaved between terminal portions of said strips and an uncarbonized portion extendable in reverse direction beyond the fold line in overlapping relation with succeeding portions of the folded strips, and anchor means for holding the transfer material against travel motion while the strips are being advanced relative thereto. 15
6. A cartridge type manifolding packet for quick reloading of a manifolding register, including superposed continuous strips of series connected detachable forms reversely folded at spaced intervals in zig-zag formation into a succession of layers, a manifolding sheet interleaved between the terminal portions of the strips, said sheet being longer than the length of a fold of the strips but less than two such lengths and reversely folded collectively with the strips about one end of a layer thereof, comprising a transfer portion interleaved between the terminal set of forms of said strips and a non-transfer continuing portion extending in reverse direction beyond the fold line of the strips into overlapping relation with a succeeding set of forms, and means for attaching the manifolding sheet to a form dispensing apparatus for holding the sheet against travel motion while the strips are being advanced relative thereto. 20
7. A cartridge type manifolding packet for quick reloading of a manifolding register, including superposed continuous strips of series connected detachable forms reversely folded at spaced intervals in zig-zag formation into a succession of layers, a relatively short manifolding sheet interleaved between terminal portions of the strips and collectively folded therewith about an end of a layer thereof, the continuing reversely folded portion beyond the fold line thereof having cut-outs therein for avoidance of strip engaging means of a strip dispensing apparatus, and means for anchoring the sheet to such dispensing apparatus for holding the sheet against travel motion while the strips are being advanced relative thereto. 25
